**DESIGN FOR A REFRIGERATING DISPLAY
CABINET**

Leonard F. Clerc, Chicago, Ill.

Application March 9, 1939, Serial No. 83,467

Term of patent 14 years

To all whom it may concern:

Be it known that I, Leonard F. Clerc, a citizen of the United States, residing at Chicago, in the county of Cook and State of Illinois, have invented a new, original, and ornamental Design for a Refrigerating Display Cabinet, of which the following is a specification, reference being had to the accompanying drawing, forming part thereof, and in which:

Figure 1 is a front elevational view of the re-

frigerating display cabinet, showing my design;

Figure 2 is a top plan view thereof;

Figure 3 is a left end elevational view thereof; and,

Figure 4 is a right end elevational view thereof.

I claim:

The ornamental design for a refrigerating display cabinet, as shown.

LEONARD F. CLERC.
